H. B. TROTT

BELT SHIFTER AND THE LIKE

Filed Feb. 25. 1927

INVENTOR
Harvey B. Trott

UNITED STATES PATENT OFFICE.

HARVEY B. TROTT, OF MCKEESPORT, PENNSYLVANIA.

BELT SHIFTER AND THE LIKE.

Application filed February 25, 1927. Serial No. 170,854.

This invention relates to safety operating mechanisms for belt shifters and the like and has for its object the provision of mechanism of this class which will alternately shift an object in opposite directions, and which will automatically lock the object against accidental movement when said object is not being shifted.

Another object is to provide a mechanism of the class described, having the novel construction, design, and combination of parts hereinafter described and illustrated in the accompanying drawings.

In the drawings—

Figure 1 is a side elevation, partly in section, of a belt shifter embodying my invention.

Figure 2 is a vertical sectional elevation taken at right angles to Figure 1.

Figure 3 is a plan view of the operating mechanism of Figure 1, one half being in section.

Referring more particularly to the drawings, the numeral 10 designates the housing of the device which is provided at its upper ends with a pair of bracket arms 20 in which a shaft 16 is secured. A belt shifting fork 15 is slidably mounted on the shaft 16 and is adapted to be shifted longitudinally of the shaft to shift the belt A, shown in Figure 2.

A substantially inverted T-shaped rocker member 8 is pivotally mounted on a fixed pivot pin 9 in the housing 10 and has the free end of its stem portion bifurcated, as at 9^a, to receive a pin 14 secured in the belt shifting fork 15, thereby forming a combined pivotal and sliding connection between the belt shifting fork 15 and the rocker member 8.

The transverse or head portion of said T-shaped rocker member 8 has its ends bifurcated, as at 9^b, to receive pivot studs or pins 6 and 7 adjacent the upper ends of link members 4 and 5, respectively, which link members are substantially T-shaped in cross-section and are slidably mounted in guideways 21 in the housing 10 for vertical movement.

The link members 4 and 5 are cut away to form clearance recesses which terminate at their lower ends in square shoulders 22, and at their upper ends in inclined shoulders 23 for purposes to be described.

A tubular boss 24 is formed on the lower end of the housing 10 and a plunger 2 is

slidably mounted in the boss 24 for vertical reciprocating movement.

A shoulder flange 25 is formed adjacent the lower end of the plunger 2 having a greater diameter than the bore of the boss 24 so as to limit the upward movement of the plunger, and an eye 26 is formed on the lower end of the plunger to which an operating cord 1 or the like is secured for pulling the plunger downwardly.

The plunger 2 is provided with a head member composed of a horizontal base 2^a and a vertical back plate 2^b, and a coiled spring 12 is mounted around the shank of the plunger 2 and has its lower end engaged against the boss 24 and its upper end engaged against the under side of the base plate 2^a of the plunger head, whereby said spring will normally urge the plunger upwardly into retracted position and will automatically retract said plunger after it is extended by pulling on the cord 1.

The upper end of the back plate 2^b of the plunger head is provided with a lug or tooth 27 adapted to be engaged in recesses 28 in the hub of the rocker member 8 to lock the rocker member against movement while the plunger is in retracted position. The recesses 28 are spaced around the hub of the rocker 8 so as to be in line with the lug 27 when the rocker member is in either extreme position.

A trigger member 3 is pivotally mounted on a headed stud 11 secured in the back plate 2^b of the plunger head and is provided with integral transversely extending trigger arms 3^b and 3^c which extend into the cut-away portions of the link members 4 and 5, respectively. A friction washer 13 is mounted between the head of the stud 11 and the trigger member 3 to retard the pivotal movement of the trigger member.

In operation, assuming that the apparatus is in the position shown in the drawings and it is desired to shift the belt shifting member or fork 15, the operator will pull on the cord 1 so as to pull out or extend the plunger 2, thereby withdrawing the locking lug 27 from the notch 28 and freeing the rocker 8 and also moving the trigger down until its arm 3^b engages the square shoulder 22 on the link 4, when the link 4 will be compelled to move downward with the trigger and plunger, thus pulling on the transverse portion of the rocker 8 and causing it to rock about the pivot pin 9 and thereby

shift the belt shifting fork 15 along the shaft or bar 16. When the trigger arm 3^b engages the square shoulder 22 the trigger member will be rocked or rotated about the pivot pin 11 until the arm 3^c engages the bottom or base plate 2^a of the plunger head, which movement will move the arm 3^c out of the line of travel of the square shoulder 22 on the link 5 which link is moved upwardly as the link 4 moves down.

After the operator has pulled on the cord 1 so as to extend the plunger 2 its entire length, or substantially its entire length, he will release the cord and the spring 12 will automatically return or retract the plunger 2 and cause the lug 27 to enter the other recess or notch 28 so as to lock the rocker 8 against movement. During the retracting or return movement of the plunger 2, the trigger arm 3^b will be moved up against the inclined shoulder 23 of the link 4 so as to rock the trigger 3 about the pivot pin 11 sufficiently to move the arm 3^c into the line of travel of the square shoulder 22 on the link 5. Now, if it is desired to return the belt shifting fork 15 to the position shown in the drawings, the operator will again pull on the cord 1 and extend the plunger 2 so as to release the rocker 8 and cause the trigger arm 3^c to engage the square shoulder 22 on the link 5, and pull down the link 5, as described for the link 4.

While I have described and shown the above novel mechanism as being positioned vertically, it will be understood that I do not wish to be limited to mechanism so positioned since the mechanism of this invention will operate equally as well when positioned horizontally or at any desired angle. It will also be understood that while I have shown the novel operating mechanism of this invention as used for operating or shifting a belt shifting fork, I do not wish to be limited to such use since such mechanism may be used for shifting or operating various other elements where a shifting or throwing movement is desired.

I claim—

1. An operating mechanism comprising a housing, a substantially inverted T-shaped rocker member pivotally mounted on a fixed pivot in said housing, a pair of links pivotally secured to the opposite ends of the transverse portion of said rocker member and slidably mounted in said housing, inwardly extending shoulders adjacent the lower end of each of said links, a plunger mounted for reciprocatory movement in said housing, a trigger head pivotally mounted on the inner end of said plunger and having trigger arms extending outwardly from each side thereof, means for limiting the pivotal movement of said trigger head relative to said plunger, means for reciprocating said plunger, one of said trigger arms being adapted to engage

the shoulder on one of said links upon one reciprocatory movement of said plunger so as to pull said link and rock said rocker member in one direction, and the other trigger arm being adapted to engage the shoulder on the other of said links upon the alternate reciprocatory movements of said plunger so as to pull said link and rock said rocker member in the other direction, and means for locking said rocker member against movement when said plunger is at rest.

2. An operating mechanism comprising a housing, a substantially inverted T-shaped rocker member pivotally mounted on a fixed pivot in said housing, a pair of links pivotally secured to the opposite ends of the transverse portion of said rocker member and slidably mounted in said housing, inwardly extending shoulders adjacent the lower end of each of said links, a plunger mounted for reciprocatory movement in said housing, a trigger head pivotally mounted on the inner end of said plunger and having trigger arms extending outwardly from each side thereof, means for limiting the pivotal movement of said trigger head relative to said plunger, means for reciprocating said plunger, said trigger arms being adapted to alternately engage the shoulders on the respective ones of said links upon alternate reciprocations of said plunger so as to alternately pull said respective links and thereby alternately rock said rocker member in opposite directions.

3. The combination with a shiftable member, of means for shifting said member in opposite directions, said means comprising a housing, a substantially inverted T-shaped rocker member pivotally mounted on a fixed pivot in said housing and having its stem portion connected to said shiftable member by a combined pivotal and sliding connection, a pair of links pivotally and slidably connected to the opposite ends of the transverse portion of said rocker member and slidably mounted in said housing, inwardly extending shoulders adjacent the lower end of each of said links, a plunger mounted for reciprocatory movement in said housing, a trigger head pivotally mounted on the inner end of said plunger and having trigger arms extending outwardly from each side thereof, means for limiting the pivotal movement of said trigger head relative to said plunger, means for extending said plunger, a spring for retracting said plunger, said trigger arms being adapted to alternately engage the shoulders on the respective ones of said links upon alternate extensions of said plunger so as to alternately pull said respective links and thereby alternately rock said rocker member in opposite directions.

4. The combination with a shiftable member, of means for shifting said member in opposite directions, said means comprising a housing, a substantially inverted T-shaped 5 rocker member pivotally mounted on a fixed pivot in said housing and having its stem portion connected to said shiftable member by a combined pivotal and sliding connection, a pair of links pivotally and slidably 10 connected to the opposite ends of the transverse portion of said rocker member and slidably mounted in said housing, inwardly extending shoulders adjacent the lower end of each of said links, a plunger mounted for 15 reciprocatory movement in said housing, a trigger head pivotally mounted on the inner end of said plunger and having trigger arms extending outwardly from each side thereof, means for limiting the pivotal movement of 20 said trigger head relative to said plunger, means for extending said plunger, a spring for retracting said plunger, said trigger arms being adapted to alternately engage the shoulders on the respective ones of said links 25 upon alternate extensions of said plunger so as to alternately pull said respective links and thereby alternately rock said rocker member in opposite directions so as to shift said shiftable member in opposite directions, 30 and means for locking said rocker member against movement when said plunger is retracted.

5. A mechanical belt shifter comprising a

housing, a shaft mounted in said housing, a belt shifting member slidably mounted on 35 said shaft and adapted to be shifted longitudinally of said shaft, a substantially inverted T-shaped rocker member pivotally mounted on a fixed pivot in said housing and having its stem portion connected to said 40 belt shifting member by a combined pivotal and sliding connection, a pair of links pivotally and slidably connected to the opposite ends of the transverse portion of said rocker member and slidably mounted in said housing, inwardly extending shoulders adjacent the lower end of each of said links, a plunger 45 mounted for reciprocatory movement in said housing, a trigger head pivotally mounted on the inner end of said plunger and having trigger arms extending outwardly from each side thereof, means for limiting the pivotal movement of said trigger head relative to said plunger, means for extending said plunger, 50 a spring for retracting said plunger, said trigger arms being adapted to alternately engage the shoulders on the respective ones of said links upon alternate extensions of said plunger so as to alternately pull said 55 respective links and thereby alternately rock said rocker member in opposite directions so as to shift said belt shifting member in opposite directions, and means for locking said rocker member against movement when said plunger is retracted.

HARVEY B. TROTT.
